UNITED STATES PATENT OFFICE.

ONESIME GALARNEAU, OF MONTREAL, CANADA, ASSIGNOR TO ADELARD
EMILE CHARRON, OF SAME PLACE.

ICE-CREEPER.

SPECIFICATION forming part of Letters Patent No. 625,330, dated May 23, 1899.

Application filed March 28, 1898. Serial No. 675,522. (No model.)

To all whom it may concern:

Be it known that I, ONESIME GALARNEAU, a citizen of the Dominion of Canada, residing in the city and district of Montreal, Province of Quebec, Canada, have invented certain new and useful Improvements in Ice-Creepers, (for which Letters Patent of the Dominion of Canada were granted May 4, 1898, No. 59,848, the application for which was filed on 5 March 26, 1898, Serial No. 81,201;) and I do hereby declare the following to be a clear, full, and exact description of the invention, such as will enable others skilled in the art to which it appertains to make and use the 10 same.

My invention relates to improvements in ice-creepers.

The object of my invention is to provide a device which can be readily attached to or 20 detached from the shoe or rubber and which can be readily placed into and out of position when affixed to the shoe or rubber.

A further object is to provide an ice-creeper which is neat and attractive in appearance, 25 durable in construction, and which can be made at a moderate cost.

To these and other ends my invention consists in the improved construction and combination of parts hereinafter fully described, 30 and particularly pointed out in the appended claims.

In the drawings, in which similar letters of reference indicate similar parts in both views, Figure 1 is a bottom plan view of a shoe provided with an ice-creeper formed in accordance with my invention. Fig. 2 is a side elevation of the same.

A designates my improved ice-creeper, formed of the attaching-dogs a and the spur-carrying frame a' . The spur-carrying frame a' is preferably formed as shown in the drawings, having the form of a bow, and to one face of the bow-frame are formed integral spurs a^2 , which are adapted to engage with the ice. The ends of the bow-frame are extended laterally and screw-threaded, as at a^3 , for a purpose hereinafter described. A suitable screw-threaded pin a^4 is mounted in suitable openings formed in the bowed portion 45 and serves to draw the attaching-lugs a against the heel of the boot or shoe in order

that they may hold the creeper in position. The attaching-lugs a are provided with screw-threaded openings, by means of which the attaching-lugs a are connected to the ends of 55 the bowed frame.

The creeper is attached to the heel of the shoe by first rotating the attaching-lugs on the screw-threaded ends of the bowed frame until the distance between them about equals 60 the width of the heel, after which the creeper is held against the heel and the pin a^4 rotated, and thus tightening the attaching-lugs against the sides of the heel. The position of the creeper is as shown in Fig. 1, as in this manner the weight of the user will serve to cause 65 the spurs to enter the ice without fail and without any danger of the spurs slipping, the only possible movement being a rotatory one, and the size of the creeper, together with the 70 distance of the spurs from the pivotal point, preventing any liability of the rotatory movement.

When it is desired to turn the spurs to an inoperative position, the creeper is rotated on 75 its pivotal points and within the attaching-lugs to the position shown in dotted lines in the drawings, thus putting the creeper into a position where the spurs project inwardly and will not engage with the carpet and other 80 objects. When the creeper is in its inoperative position, it will be obvious that the lower face of the attaching-lugs and face of the bowed frame will form an extended surface on the bottom of the heel on which the wearer 85 can walk without any danger of injuring carpets, &c., and which will not have any tendency to cause the wearer any inconvenience or accidental falling. Another advantage lies in the position of the pin a^4 , being placed 90 so that the wearer can easily reach it and detach the lugs without difficulty.

Having thus described my invention, what I claim as new is—

1. An ice-creeper, comprising a spur-carrying frame; spurs formed on one face of said frame; attaching-lugs rotatively mounted on said frame; and a screw-threaded pin mounted on said frame, adapted to removably secure said attaching-lugs to the side of a heel. 95

2. An ice-creeper, comprising a "bow-shaped" spur-carrying frame, the ends of said 100

frame extending laterally from said frame and provided with screw-threads; spurs formed on one face of said frame; and attaching-lugs adjustably and rotatively mounted on 5 said screw-threaded ends, said lugs being adapted to engage with the side of a heel.

3. An ice-creeper, comprising a spur-carrying frame; spurs formed on one face of said frame; attaching-lugs adjustably and rotatively mounted on said frame; and a threaded 10

pin, mounted on said frame, adapted to move said attaching-lugs into and out of engagement with the side of a heel, substantially as described.

In witness whereof I have hereunto set my 15 hand in the presence of two witnesses.

ONESIME GALARNEAU. [L. S.]
